UNITED STATES PATENT OFFICE

129,191

DESIGN FOR A SUIT

Samuel Salsky, Brooklyn, N. Y.

Application June 21, 1941, Serial No. 101,585

Term of patent 3½ years

To all whom it may concern:

Be it known that I, Samuel Salsky, a citizen of the United States of America, residing in Brooklyn, county of Kings and State of New York, have invented a new, original and ornamental Design for a Suit, of which the following is a specification, reference being had to the accompanying drawing, forming part thereof.

Fig. 1 is a front view of a suit showing my new design.

Fig. 2 is a rear view thereof.

The characteristic feature of my design resides in the combination on the suit disclosed of the specific shoulder yoke in association with the front neckline and button panel as shown.

I claim:

The ornamental design for a suit, substantially as shown and described.

SAMUEL SALSKY.
